PROTECTIVE MASK

John Coccellato, San Francisco, Calif.

Application June 23, 1943, Serial No. 491,900

5 Claims. (Cl. 2-8)

1

The invention relates to a head-mounted mask for use by mechanics and other workers to protect their eyes and faces against injurious conditions inherent to their occupations.

An object of the invention is to provide a general-utility mask which is adaptable to its advantageous use by workmen in a variety of vocations.

Another object is to provide an improved mask structure including a goggles arranged for its resilient and direct fitted seating against the wearer's face when in use.

A further object is to provide an improved means for directly mounting the goggles on a head-piece or harness for its ready adjustment between its self-seating use position and a non-use position in which it is free of the wearer's head while supported therefrom.

An added object is to provide a mask structure of the character described having a face shield thereof displaceably mounted on the goggles for its optional use.

Yet another object is to provide a particularly effective means for removably mounting a face shield on a goggles with which it is usable to provide a complete face-shielding mask.

The invention possesses other objects and features of advantage, some of which, with the foregoing, will be set forth or be apparent in the following description of typical embodiments thereof, and in the accompanying drawings in which,

Figure 1 is a side elevation of one embodiment of a complete mask assembly mounted in use position on a person's head, a non-use disposal of the masking assembly being indicated in dash lines.

Figure 2 is a sectional elevation taken at the line 2-2 in Figure 1.

Figure 3 is an enlarged fragmentary section taken in a fore-and-aft and upright central plane of the mask.

Figure 4 is an enlarged top view of the mask, portions of the structure being broken away to disclose certain details thereof.

Figure 5 is a longitudinal view through a linkage connecting the mask proper and a supporting head-piece.

Figure 6 is an enlarged fragmentary sectional view taken at the line 6-6 in Figure 2.

Figure 7 is a fragmentary section at the line 7-7 in Figure 6.

Figure 8 is a view showing the elements of Figure 6, but with a shield-securing member transversely displaced from its operative position.

2

Figure 9 shows another embodiment of the mask in a view corresponding to that of Figure 1, a displaced position of a face-shield element of the mask being indicated in dash lines.

5 Figure 10 is an enlarged fragmentary section taken in a fore-and-aft and upright central plane of the mask of Figure 9.

Figure 11 is an enlarged side elevation showing the mask of Figure 9 as having its masking assembly displaced in non-use position with respect to a wearer's face.

Figure 12 is an enlarged top view of the mask of Figure 9, portions of the structure being broken away.

15 Figure 13 is a fragmentary section at the line 13-13 in Figure 12.

Figure 14 is a section showing the relation of the members of Figure 12 when the face-shield element is disposed in the dash-line position shown for it in Figure 9.

20 Two embodiments of mask assemblies disclosing the features of my invention are shown and hereinafter described, and these assemblies have been particularly designed for mounting on the head

25 of a worker for protecting his eyes and face against such industrial hazards as undue heat, intense light, actinic rays, flying sparks and other particles, spattering metal, etc., which arise in different occupations, such as welding and grinding and forging and coating, etc. A mask unit

30 embodying my invention essentially comprises an eye shield or goggles arranged for fitted engagement against a worker's face, a face shield displaceably mounted on the goggles for completing the face protection as required, a suitable head-piece for fitted disposal on the worker's head, and a mounting connection between goggles and head-piece such that the goggles may be dis-

35 placeably and sealedly held against the wearer's face when in use.

40 As is particularly illustrated, similar head-piece structures 16 are utilized in both of the mask assemblies shown, and said structures each comprise a flexible band 17 which is arranged to fittedly encircle the head of the wearer at the brow line and has opposite side points thereof connected by an arched band 18 which comprises a crown band of the head-piece; the present head-piece 16 is

45 of the nature of a head harness or cap, and may be so considered and referred to. For fitting the head-piece 16 to a particular worker's head, the band 17 is preferably of adjustable length; as shown, the band is split at its rear, and its rear

50 ends are telescopically engaged in a sleeve mem-

55 ber 19 which is secured to the head-piece 16 at its front end.

ber 19 from its different ends to permit an adjustment of the band length.

The effective length of the band 17 may be positively adjusted and fixed by any suitable means; as shown, ears 20 extend outwardly from the different band ends and in mutually spaced relation through a slot 21 provided intermediately in the outer side of the sleeve 19, and are connected by a compound screw 22 having an intermediate head from which oppositely threaded shank portions extend through nuts provided on the different ears. The front portion 23 of the band 17 comprises a brow band, and may be so referred to. The head-encircling band 17 and the crown band 18 may be of metal, but are preferably of a material which is non-inflammable and is non-conductive with respect to heat and electricity; a sheet fibre or a plastic meet these requirements.

By reference to the embodiment of Figures 1 to 8 inclusive, it will be seen that the goggles 24 of this mask assembly comprises a tubular body 25 of rectangular cross-section providing a rectangular sight opening 26 at its front at which one or more suitable transparent lenses or panes are mounted for protective disposal in front of both eyes of a user of the mask. In the present structure, and in terms of a use positioning of the mask, the flat upper and lower body walls 27 and 28 respectively are mutually parallel and are perpendicular to the plane of the sight opening 26, while the flat side walls 29 of the body diverge rearwardly from said plane and make equal angles therewith.

The rear edges of the various body walls 27 and 28 and 29 are shaped for simultaneous line engagements with the opposed portions of the wearer's face; as shown, the rear edge 27' of the top wall 27 is concavely curved to fittedly receive the wearer's forehead below the brow band 23, the rear edge 28' of the bottom wall 28 is concavely curved and notched to fittedly engage the profile of the wearer's cheeks and nose at its line of engagement with the face, and the rear edges 29' of the side walls 29 are straight and mutually parallel in a plane parallel to that of the sight opening and at which the rear body edges 27' and 28' terminate.

A continuous inturned flange 31 at the forward ends of the body side walls defines the sight opening 26 and provides a seat for the mounting against and behind it of one or more panes or lenses, a single lens 32 being particularly shown in the present assembly as representing any desired type of lens or combination of lenses. In accordance with the particular use conditions for the goggles, the lens or lenses used would have various light-screening qualities or solely provide a transparent protection of the eyes and the covered face portion against heat and/or flying particles.

For releasably securing a lens or lenses in place behind the flange 31, a member 33 of resilient sheet material is sprung forwardly into place between the forward edges of upright stop members 34 extending inwardly from the body side walls 29 and the rear face of the lens 32 at its top and bottom edges, said member 33 being provided with an interior opening opposite the sight opening 26 and essentially comprising a releasable leaf-spring means. The present stop members 34 are shown as comprising elongated flat elements intermediately pivoted upon the side walls 29 for swinging in their planes, whereby they may assume thrust-balanced positions as

seat members for the ends of the spring 33 engaging their forward edges.

Inwardly of its forward end plane, the goggles body 25 is provided with a continuous flange 35 extending outwardly and arranged for use in mounting a suitable face shield element on the goggles. As shown, the flange 31 defining the sight opening 26 and the shield-attachment flange 35 comprise integral parts of the body 25, which body is preferably formed of a material which is non-inflammable and a poor conductor of heat, and may be of a moldable material or fire-proofed wood. While such is not specifically shown, it will be obvious that a special light-sealing means might be provided about the edges of an installed lens.

In general terms, the connection of the goggles 24 with the head-piece 16 is effected by means of a tension linkage so connecting the goggles and head-piece that, with the goggles positioned beneath the brow band 23, as in Figures 1 and 9, the goggles are resiliently held in fitted position against the wearer's face entirely by the action of the tension linkage provided. As shown in Figures 1 and 3 and 4 and 5, said tension linkage comprises assemblies 36 pivotally connected with the goggles and head-piece at corresponding points at their opposite sides by means of hinge pins 37 and 38 respectively. The hinge pins 37 extend transversely outwardly through and from the goggles body sides 29 at corresponding intermediate points of said sides, while the hinge pins 38 extend laterally outwardly through and from the band 17 of the head-piece structure at its extreme side points; in the present structure, the extremities of the crown band 18 are fixed to the band 17 at said points whereby to provide a double thickness of the head-piece band material therat and so provide for a particularly rigid mounting of the pins 38 on the head-piece.

It will now be noted that each linkage assembly 36 essentially comprises a tubular member 39 telescopically and slidably receiving a cylindric member 41 in its bore and connected with the latter member by means of a spring 42 in such a manner that the spring 42 constantly urges a drawing of the member 41 within the member 39 to a permitted limit. In the present structure, and as brought out in Figure 5, the outer end of the member 41 is provided with an eye 43 for freely receiving a hinge pin 37 or 38, while a plug member 44 fixed in the other end of the tubular member 39 provides an eye 45 at its outer end for freely receiving a hinge pin 37 or 38.

At their opposed inner ends, the plug 44 and the member 41 are provided with eyes 46 and 47 respectively for the connection of the helical tension spring 42 to and between the plug and member to constantly urge the drawing of the member 41 within the member 39 to the permitted limit. Stop pin 49 extending inwardly from the member 39 into a longitudinal side slot 50 of the member 41 prevents a relative turning of the members, and the different slot ends normally prevent the removal of the member 41 from the member 39 and limit the extension of the member 41 into the member 39; as indicated, the pin 49 comprises a screw which is threadedly engaged through the side of the member 39 at an appropriate point thereof.

In the present instance, the pins 37 and 38 are formed generally as split rivets, engage freely through the eyes 43 and 45, fit rotatably through openings in the body sides 29 and the head band 17 with their heads opposite the inner faces of

the sides and head, have their points turned outwardly for retaining an eye receiving them, and have helical compression springs 51 enclosing their shanks between the eyes and the goggles body or head-piece which mounts them. As shown, the pins 37 are utilized to provide the pivoted mounting of the spring seat members 34 by their engagement through transverse openings of the members which are engaged between the pin heads and the opposed faces of the body sides 29. This goggles mounting arrangement laterally spaces the linkage assemblies 36 from the goggles and head-piece, provides a desirable degree of frictional resistance to relative adjustments of the goggles and head-piece, and secures the pins in their mounted positions through the goggles body and the band 17 of the head-piece.

A further and particularly noteworthy advantage of the present arrangement for mounting the goggles on the head-piece is the fact that the springs 51 are cooperative to urge a symmetrical relation of the goggles to the head-piece while permitting any variation for such symmetrical relation which is required for a fitted bearing of the continuous inner goggles edge against a wearer's face, it being understood that the pin connections at the terminal eyes of the linkage assemblies are universal to the required degree. Preferably, and as shown, the planes of the sides 29 of the goggles body 25 extend generally parallel to the lines of the linkage assemblies connected to them when the goggles and head-piece are in symmetrical relation.

A face shield member 53 is provided for mounting on the goggles body 25 at the flange 35. In the present structure, the shield member 53 is circular in outline, is generally dish-shaped with an edge flange portion 53' extending rearwardly of its general plane, and is provided with an interior opening for fittedly receiving the portion of the goggles body forwardly of the flange 35 to which the member may be suitably attached. While the shield 53 might be permanently fixed against and to the flange 35, or to some other goggles body portion, a mounting of the shield on the goggles for its displacement to permit the use of the goggles without it is preferable, as this shield member may not be needed under some circumstances of use of the goggles; accordingly, the disclosed attaching means for the shield is releasable to permit the use of the goggles with or without the shield. The shield 53 is preferably formed of a non-inflammable fibre or plastic whereby it may have a minimum weight.

For the most effective disposition of the face shield 53 with respect to the goggles and a user's face, the opening thereof receiving the goggles body is eccentric to it and, in terms of its use position, adjacent its top. As shown, the means releasably fixing the positioned shield on the goggles is directly cooperative with the flange 35, and, in general terms, comprises a plurality of like clamping devices which are operative through registering holes 54 and 55 of the shield and flange respectively to cooperatively fix the shield to the flange. More specifically, the present clamping devices are mounted on a frame-like member 56 providing rearwardly projecting members 57 disposable through said holes 54 and 55 and mounting cam or toggle catches 58 at their free ends for operation against the rear face of the flange 35 to releasably clamp the flange between the catches and the frame 56, said frame acting as a common head for the members 57.

As particularly shown, the members 57 com-

prise ears extending in pairs from the member 56 and pivotably mounting the catches 58 between them at their outer ends. The catches 58 are flat and comprise eccentric edge-cam portions 58' and radially extending handle portions 58''. When a catch 58 is operative, as in Figures 6 and 7, the handle portion 58'' thereof is arranged to extend generally parallel to the flange 35 while a generally flat portion of its cam face bears as a toggle against the flange at opposite sides of the opening 55 through which the cam-carrying ears extend. When all the cam handles 58'' are extended in line with the ears 57, as in Figure 8, the member 56 and shield 53 are released for removal forwardly from the goggles body 25; the member 56 may be fixed to the shield 53 if desired.

It will now be noted that the tensionally operative linkage assemblies 36 slope upwardly from the operatively disposed goggles to the head-piece whereby they are generally operative to engage the goggles with the under side of the brow band 23 while fittedly seating the rear goggles edge against the wearer's face. When the goggles is to be displaced from its operative position, it is manually pulled outwardly against the resistance of the springs 42 of the linkage assemblies until the goggles body 25 clears the brow band 23 for its swinging upwardly to dispose the goggles body above the band. A subsequent release of the goggles permits a shortening of the linkage assemblies to their limits imposed by the pin 49 of the member 39 (as in Figure 5) whereby the raised goggles may rest on the wearer's forehead without pressure other than that of gravity, or upon the top of the brow band, the former being particularly indicated in Figure 1. In this manner, the goggles may be displaced from their use position while the head-piece is mounted in its fixed position on the user's head.

Referring now to the embodiment of Figures 9 to 14, it will be noted that this mask assembly includes a head-piece structure 16 like that of the first embodiment, a goggles 61 arranged for fitted engagement against the face of the wearer of the head-piece, a face shield 62 displaceably mounted on the goggles, and assemblies 63 connecting the goggles with the head-piece for engaging the goggles in its use position and providing for its swinging between its use and non-use positions. The body 64 of the goggles 61 is shaped and constituted generally as the body 25 of the goggles 24, having the rear edges of its upper wall 65 and its lower wall 66 and side walls 67 defining a face-fitting profile as before. At its forward end, the body 64 is provided with a continuous inturned flange 68 providing a seat for an appropriate lens or pane 69 which is removably held in place by a spring frame 70 which is flexed between it and a spring-seat member 71 corresponding to the member 34 of the first embodiment. The body 64 would preferably be molded or cast of a non-inflammable and light-weight material.

Each present linkage assembly 63 comprises a pair of links 72 and 73 hingedly connected by a pin 74 at mutually engaged ends thereof, and having their other ends provided with eyes which freely receive pins 75 and 76 extending outwardly from opposite sides of the goggles body 64 and head-piece 16 respectively. The hinge-pins 75 and 76 extend through helical compression springs 77 which are engaged between the links and the elements from which the corresponding pins 75 and 76 extend, the disclosed pivoted engagement of the links with the goggles and head-piece being

the same as that providing the connections of the linkage assemblies 36 of the first embodiment.

An helical spring 78 connects intermediate points of the links 72 and 73 of each assembly 63, said spring being arranged to be in tension when the goggles of the mounted mask is operatively disposed in front of the wearer's eyes, the links 72 and 73 then being angularly related whereby the spring 78 urges a shortening of the connection provided between the goggles and head-piece. As shown, the link-connecting hinge pins 74 are disposed above the plane of the hinge pins 75 and 76, whereby this linkage never lies opposite the uncovered face side portions below the head-piece brow band 23. It is to be noted that the action of the resiliently tensed connections thus provided between the goggles and head-piece may resiliently engage the top of the goggles body 64 with the lower edge of the brow band 23 by reason of the obliquity of the line of action of the link assemblies with respect to the plane of the brow band, this action corresponding to the goggles-seating action provided by the tension linkage of the first embodiment.

In the present structure, the face shield 62 is hingedly mounted on the goggles for its displacement from a cooperative relation to the goggles without requiring its dismounting therefrom. As particularly shown, the face shield 62 is shaped as the shield 53 of the first embodiment, and is fixedly carried on a member 78 which frames its sight opening and is directly hinged to the goggles body 64 for its swinging adjustment about an axis above and parallel to the top line of the sight opening at the forward end of the goggles body. In the present structure, laterally spaced arms 79 extend upwardly from forward points of the top of the body 64, and arms 81 extend upwardly from the top of the frame member 78 to a hinged connection of their upper ends with the arms 81. The opposed faces of the goggles body 64 and the member 78 are complementarily formed for a light-tight fitted engagement when the shield is operatively disposed with respect to the goggles, and means are provided for optionally securing the shield in operative and inoperative relations to the goggles.

As particularly brought out in Figures 12 and 13 and 14, the hinge arms 79 are formed to provide forwardly-opening rectangular channels at their upper ends, and the upper ends of the hinge arms 81 are engaged and hingedly held in said channels by mutually aligned hinge pins 82 extending through them and the channel sides. Springs 83 are so engaged between the arms 79 and 81 adjacent the hinging points of the arms that they are operative to yieldingly urge a retention of the face shield 62 in the limiting operative and inoperative positions shown for it, while permitting a shifting of the shield between said positions through a dead-center position. In the present structure, the springs 83 are C-shaped, are disposed in the plane of relative swinging of associated hinge arms 79 and 81, and are pivotally connected to the respective arms by means of pins 84 and 85 mounted therein, each arm 81 being recessed from its rear face to receive the spring end which is attached to it by the pin 85.

The present shield-carrying frame 78 may, as is shown, mount a supplementary screening lens 86 behind a continuous inturned flange 87 at its

forward end which preferably provides a sight opening no smaller than that provided by the flange 68 which defines the effective sight opening for the goggles 61, the present arrangement providing a secondary or supplementary goggles. The lens 86 is held in place by a frame-like leaf spring 88 which is reactive against the lens 86 behind top and bottom points thereof and reaction ribs 89 extending inwardly from the side walls of the frame 78; the arrangement corresponds to the mounting means for the lens 69 of the goggles 61. It will be understood that the present structure permits an inoperative disposal of the shield 62, and the secondary goggles which mounts it, independently of the goggles 61, or a non-use disposal of the complete goggles-and-shield assembly.

An inoperative disposal of the present goggles assembly is arranged to be effected by manually pulling the goggles structure forwardly against the yielding resistance of the springs 78 of the linkage 63 so that the goggles body will clear the brow band 23, swinging the structure upwardly and out of the line of vision of the wearer, and releasing the structure to engage the band 23 and/or the wearer's forehead to secure the assembly in its displaced position, the action being reversed for replacing the assembly in its use position. When the mask is dismounted from a person's head, its parts may assume the relation shown in Figure 11 as being more compact than that of Figure 10 in which a use relation of the goggles and face shield is shown.

From the foregoing description of the invention taken in connection with the accompanying drawings, the advantages of the construction and methods of use will be readily understood by those skilled in the art to which the invention appertains. While I have described the features and principles of use of arrangements which I now consider to be preferred embodiments of my invention, I desire to have it understood that the showings are primarily illustrative, and that such changes may be made, when desired, as fall within the scope of the following claims.

I claim:

1. In a protective mask, a head-piece, a goggles arranged for its use positioning in seated engagement with the face of the wearer of the head-piece in a line about the eyes, and a tension linkage swingably mounting the goggles on the head-piece, said linkage comprising pairs of mutually engaged and relatively movable elements extending from pivot connections with the head-piece and with the goggles at corresponding opposite points thereof, and a spring means reactive directly between the elements of each pair of like elements to constantly and yieldingly urge the movement of the pivot points on the goggles toward the corresponding pivot points on the head-piece.

2. In a protective mask, a head-piece, an eye-protecting goggles arranged for its use positioning to engage the face of the wearer of the head-piece in a line adjacent and about the eyes, a resilient tension linkage swingably mounting the goggles on the head-piece and operative to resiliently seat the goggles in its use position against the wearer's face, a face shield member having an interior opening therethrough for fittedly receiving the goggles, and means mounting the face shield directly on the goggles for cooperation therewith to provide a lateral extension of the

masking area of the goggles and for its removal from its use position with respect to the operatively disposed goggles.

3. A structure in accordance with claim 1 whereof the linkage elements of a pair are tele-

scopically engaged.

4. A structure in accordance with claim 1 whereof the linkage elements of a pair are hingedly connected at the ends thereof opposite their points of attachment to the goggles and head-piece.

5. In a protective mask, a head-piece, a goggles arranged for its use positioning to resiliently bear against the face of the wearer of the head-piece in a line about the eyes, multi-section links of variable effective length independently connecting opposite side points of the goggles with corresponding opposite side points of the head-piece for a swinging displacement of the goggles between its use position and an overhead non-use

5

10 20

position, means cooperative between the sections of each link to resiliently urge a contraction of the link, and means providing pivot joint connections between the link ends and the goggles and head piece while providing a frictional resistance to swinging displacements of the goggles.

JOHN COCELLATO.
